PHOTOGRAPHIC PRINTING EASEL

Gustave Fassin, Irondequoit, N. Y., assignor to
 International Industries, Inc., Ann Arbor,
 Mich., a corporation of Michigan

Application February 27, 1939, Serial No. 258,665

9 Claims. (Cl. 88—24)

The present invention relates to photography and more particularly to an easel for photographic printing or enlarging.

One of the objects of the present invention is to provide a new and improved easel for positioning and holding a photo-sensitive sheet. Another object is to provide a photographic printing easel on which the photo-sensitive sheet may be accurately located and masked. A further object is to provide a photographic printing easel with a self-contained optical system for focussing. These and other objects and advantages reside in certain novel features of construction, arrangement and combination of parts as will hereinafter be more fully set forth and pointed out in the appended claims.

Referring to the drawings:

Fig. 1 is a top plan view of a photographic printing easel embodying my invention.

Fig. 2 is a section taken on line 2—2 of Fig. 1.

Fig. 3 is a bottom view of my easel.

Fig. 4 is a section taken on line 4—4 of Fig. 1.

Fig. 5 is a section taken on line 5—5 of Fig. 3.

Fig. 6 is an enlarged plan view of one positioning member.

Fig. 7 is a section taken on line 7—7 of Fig. 6.

Fig. 8 is an enlarged plan view of the other positioning member.

Fig. 9 is an end view thereof.

Fig. 10 is a plan view of the focussing sheet.

A preferred embodiment of my invention is illustrated in the drawings wherein 15 designates a substantially rectangular base having a flat metal plate 16 suitably secured thereto by screws 17 for receiving a photo-sensitive sheet such as a sheet of projection printing paper. Two brackets 18 and 19 are suitably secured on the bottom of the plate 16, within the base 15 as, for example, by welding or soldering. These brackets 18 and 19 are preferably positioned one on each side of the center of the plate 16 adjacent one wall of the base 15. Within the base 15, is a long, U-shaped track having two legs 20 and 21 with their free ends bent outwardly at 22 and 23 and pivotally mounted in the brackets 18 and 19 respectively. A carriage 24 is provided with two parallel grooves 25 and 26 for receiving the parallel legs 20 and 21 of the track. A resilient plate 27 is suitably secured on the carriage 24 by screws 28 and bears frictionally against the legs 20 and 21 to retain the carriage 24 in any selected position on the track.

The carriage 24 is formed with two upstanding lugs 29 and 30 which extend above the surface of the plate 16 through two parallel slots 31 and 32 respectively, as shown in Fig. 2. A leaf spring 33 is suitably secured at one end to the bottom of the plate 16 by welding, soldering or the like, and its free end engages under the closed end 34 of the track. The lugs 29 and 30 are thus resiliently urged upward through the slots 31 and 32.

A second pair of brackets 35 and 36 are suitably secured on the bottom of the plate 16 at one side of the U-shaped track. A second track 37, having legs 38 and 39 bent inwardly at 40 and 41 and pivotally mounted in the brackets 35 and 36 respectively, extends from a point near the leg 21 to ward the side wall of the base 15. This track 37 is substantially perpendicular to the legs 20 and 21 and is preferably located beneath the transverse center of the plate 16. A carriage 42 is provided with a groove 43 for receiving the track 37 and a resilient plate 44 is secured on the carriage 42 to frictionally engage the track 37. An upstanding lug 45 extends upward beyond the surface of the plate 16 through a slot 47, as shown in Fig. 2. A rod 48 is secured across the legs 38 and 39 and a leaf spring 49, secured at one end to the plate 16 engages under the cross rod 48 and urges the lug 45 upward through the slot 47.

Two blocks 50 and 51 are secured on the outside of one of the sides of the base 15 and pivotally receive the inturned ends 52 and 53 of a frame. This frame consists of two side arms 54 and 55 and a cross arm 56 and extends around the base 15 outside of the limits of the plate 16. A pair of parallel, independently movable, masking plates 58 and 59 are adjustably mounted on the arm 55 and extend across the plate 16, while a second pair of masking plates 60 and 61, adjustably mounted on the arm 56, extend across the plate 16 perpendicularly to the plates 58 and 59. The mechanism for attaching these masking plates to the arms is the same for each plate and only one such mechanism will be described. As shown in Fig. 4, the masking plate 58 is suitably fixed to a block 62 which has a groove 63 in its bottom surface for receiving the side arm 55. A screw 64, having an enlarged head 65, projects through a hole 66 in the plate 58 and block 62 and is threaded into a block 67. This block 67 has a groove 68 in its upper face to receive the side arm 55. Upon tightening the screw 64, the two blocks 62 and 67 are drawn together and the side arm 55 is clamped in the grooves 63 and 68, thus locking the masking plate 58 on the side arm 55.

In the operation of the locating mechanism of

my new easel, the lugs 29 and 30 and the lug 45 are moved longitudinally of their respective slots until they are in the desired position to locate the edges of the paper or other photo-sensitive sheet. The masking strips 58, 59, 60 and 61 are then set to mask the paper to the desired extent and are locked against movement on the frame. A sheet of paper is then placed on the plate 16 so that its edges engage the three lugs 29, 30 and 45 and the frame carrying the masking strips is pivoted down against the plate 16. The lugs 29, 30 and 45 yield under the pressure of the masking strips 58 and 61 so that the masking strips press the paper flat against the plate 16. In this way, the operator is always insured of a controllable and uniform border on his enlargements. Of course scales can be provided on the plate 16 for setting the lugs and strips.

To insure proper seating of the frame, two blocks 69, having tapered tops, are attached one on each side of the base 15. When the frame is brought down to press the paper against the plate 16, the side arms 54 and 55 engage the tapered tops of the blocks 69 and the frame and masking plates are thus automatically centered.

The plate 16 is formed with a central aperture 70 and a window of glass or other transparent material 71 is fixed in this aperture 70 so that its top surface is flush with the top surface of the plate 16. A rectangular tube 72 is attached to the plate 16 by a bracket 73. This tube is within the base 15 and extends from beneath the aperture 70 to a hole 74 in one side of the base 15. The tube 72 is preferably positioned along the center of the plate 16 between the legs of the U-shaped track. The tube 72 has an opening 75 directly beneath the aperture 70 and a reflector 76 suitably secured in the tube 72, directs light entering from this opening 75 along the axis of the tube 72. An objective lens 77 is suitably fixed in the tube 72 adjacent the reflector 76.

A right angle sleeve 78 is suitably fastened in the open end of the tube 72 outside of the base 15 and a field lens 79 is fixed in the sleeve 78 within the tube 72. A reflector 80 attached to the sleeve 78 directs light from the field lens 79 upward to an eye lens 81. This eye lens 81 is secured in a cap 82 which is threaded into the top of the sleeve 78. The cross arm 56 of the frame is bent at 83 to prevent interference between the frame and the sleeve 78.

In order to insure focus of the image in the plane of the sensitized surface of the printing paper, a sheet 84 of transparent material such as glass or film base, having the same thickness as the printing paper, is placed on the plate 16 over the aperture 71. This sheet 84 has a mark, such as the grid 85, ruled on its upper surface. The microscope carried by the tube 72 forms an enlarged image of the grid 85 and, when the image to be printed lies in the plane of this grid, it is in exact focus at the plane of the sensitized layer of the printing paper. The microscope is preferably of sufficient power to resolve the image of the grain of the film to be enlarged and hence focus is obtained with a high degree of accuracy.

My new easel can of course be used with any projection enlarger and the positioning mechanism is of great advantage even in the making of contact prints. In projection printing, the projector is focussed using the focussing sheet and the microscope before any paper is placed on the plate 16. After the projector is focussed, the sheet 84 is removed and the printing paper

substituted. This printing paper is then suitably positioned and masked as set forth above.

From the foregoing, it will be apparent that I am able to attain the objects of my invention and provide a photographic printing easel which insures proper focus of the projected image and proper positioning and masking of the photo-sensitive sheet. Various modifications can of course be made without departing from the spirit of my invention or the scope of the appended claims.

I claim:

1. A printing easel comprising a hollow base having a flat top surface for receiving a photo-sensitive sheet, said surface having two mutually perpendicular slots therethrough, a track pivotally mounted within said base adjacent and parallel to each slot, a lug slidably mounted on each track and projecting upward through each slot to engage the edges of said sheet and maintain same on said surface, means for resiliently urging each lug upward, a frame pivotally mounted on said base along one edge of said surface and extending around said surface, and a plurality of masking plates movably mounted on said frame for pressing the edges of said sheet flat against said surface and pressing said lugs down to the plane of said surface.

2. A printing easel comprising a hollow base having a flat surface for receiving a photo-sensitive sheet, said surface having a pair of spaced, parallel slots therethrough, a U-shaped track pivotally secured at its free ends within said base and extending parallel and adjacent to said slots, a carriage slidably mounted on said track, two upstanding lugs on said carriage, one in alignment with each slot, means for resiliently urging said lugs upward through said slots for engaging the edge of a photo-sensitive sheet to position said sheet on said surface, said surface having a third slot therethrough substantially perpendicular to said pair of slots, a second track pivotally secured within said base and having a portion extending parallel and adjacent to said third slot, a second carriage slidably mounted on said portion, a third upstanding lug on said second carriage in alignment with said third slot, means for resiliently urging said third lug upward through said third slot for engaging the edge of said photo-sensitive sheet to position said sheet on said surface, a frame pivotally mounted on said base along one edge of said surface, said frame having an arm parallel to said pair of slots and a second arm parallel to said third slot, and a pair of parallel masking plates adjustably mounted on each arm to overlie the edges of a photo-sensitive sheet positioned by said lugs.

3. A printing easel comprising a hollow base having a flat surface for receiving a photo-sensitive sheet, said surface having a central aperture therethrough, a microscope mounted within said base and extending parallel to said surface from said aperture to an observation point outside the confines of said base, means mounted within said base for directing light entering through said aperture along the optical axis of said microscope, a plurality of stops yieldably extending upward from said surface for engaging the edges of a photo-sensitive sheet to position said sheet on said surface over said aperture, and a plurality of masking strips adjustably carried by said base for engaging the face of said sheet and pressing said sheet again said surface.

4. A printing easel comprising a hollow base having a flat surface for receiving a photo-sensi-

tive sheet, said surface having a central aperture therethrough, a focussing target carried by said surface above said aperture, light deflecting means secured within said base beneath said aperture for deflecting light from said aperture substantially parallel to said surface, a microscope objective mounted within said base in alignment with said light deflecting means for forming an image of said target, means carried by said base and extending beyond the confines of said base in alignment with said objective for observing said image, said surface having a slot extending therethrough substantially parallel to the axis of said objective, a track pivotally mounted within said base adjacent and parallel to said slot, a lug slidably mounted on said track, said lug having a portion adapted to project upward through said slot to engage one edge of a photo-sensitive sheet and position said sheet on said surface, said surface having a second slot therethrough substantially perpendicular to the first named slot, a second track pivotally mounted within said base adjacent and parallel to the second slot, a second lug slidably mounted on said second track, said second lug having a portion adapted to extend upward through said second slot to engage the edge of said photo-sensitive sheet and position said sheet on said surface, and a plurality of masking plates adjustably carried by said base above said surface to overlie the edges of said sheet.

5. A printing easel comprising a hollow base having a flat surface for receiving a photo-sensitive sheet, said surface having an aperture therethrough, a transparent plate fixed in said aperture with its top surface substantially flush with said flat surface, means for supporting a focussing mark over said plate and above the plane of said surface by an amount equal to the thickness of a photo-sensitive sheet, light deflecting means within said base for directing light from said aperture substantially parallel to said flat surface, an objective lens mounted within said base in alignment with said light deflecting means for forming an image of a focussing mark carried by said supporting means, said base having an aperture therethrough facing said lens and light deflecting means, and an eyepiece carried by said base in alignment with said last named aperture for receiving said image.

6. A printing easel comprising a hollow base having a flat surface for receiving a photo-sensitive sheet, said surface having an aperture therethrough, a transparent focussing sheet removably carried by said surface above said aperture, said focussing sheet having substantially the thickness of the photo-sensitive sheet, a mark on the top surface of said focussing sheet, light deflecting means mounted within said base beneath said aperture for receiving light from said mark and directing it substantially parallel to said flat surface, an objective lens mounted in said base in alignment with said light deflecting

means for forming an image of said mark, an opening in said base in alignment with said objective lens, a reflector carried by said base in alignment with said opening for directing the image forming rays from said lens upward past said flat surface, and an ocular carried by said base for observing said image.

7. A printing easel comprising a supporting wall having an opening therethrough, a flat plate carried by said wall for receiving a photo-sensitive sheet, said plate having an aperture therethrough, a focussing mark carried by said plate above said aperture, a tube secured on the bottom of said plate beneath said aperture and projecting through the opening in said wall, said tube having an aperture in alignment with the aperture in said plate, a reflector mounted in said tube beneath said apertures for directing light from said apertures along said tube, an objective lens mounted in said tube for forming an image of said mark, and an ocular carried by said plate in alignment with said opening for observing the image formed by said objective lens.

8. A photographic printing easel comprising a hollow base having a flat surface for receiving a photosensitive sheet, said surface having a central aperture therethrough, a microscope mounted within said base and extending from said aperture and parallel to said flat surface to an observation point beyond the confines of said base, means mounted within said base for directing light entering said aperture to said microscope, a pair of brackets mounted within said base, one on each side of said microscope, a U-shaped track pivotally mounted in said brackets and extending parallel to said microscope and said flat surface to a point beyond said aperture, said surface having a pair of slots therethrough parallel to said track, a carriage slidably mounted on said track, a pair of lugs on said carriage projecting upward through said slots above said surface to engage the edge of a photosensitive sheet, means for resiliently urging said carriage upward toward said surface, a frame pivotally at one edge of said base and extending around said base, and a plurality of masking strips adjustably mounted on said frame for engaging a photosensitive sheet and pressing it against said flat surface.

50 9. A printing easel comprising a flat plate for receiving a photo-sensitive sheet, said plate having an aperture therethrough, means secured to said plate for holding said plate in spaced relation to a support, a focusing mark carried by said plate above said aperture, means secured to said plate beneath said aperture for directing light passing through said aperture beneath and parallel to said plate, an objective lens positioned in the path of the light from said aperture and an ocular carried by said plate adjacent the edge thereof and in alignment with said objective for observing the image formed by said objective.

GUSTAVE FASSIN.
